HANDLE

William F. Kaspar, Keyport, N.J., assignor of one-half to John Charles Scoras, Union Beach, N.J.

Application July 14, 1955, Serial No. 522,009

1 Claim. (Cl. 287—98)

This invention relates to handles and more particularly to a two piece pivotally connected handle. Handles such as those used for a mop are usually constructed as a single straight element and of course in house cleaning operations this precludes the use of the mop to reach under furniture without stooping or bending the body to an extremely low position. In order that this type of cleaning operation may be conducted without bending or stooping, the mop handle must either bend or break with a swivel joint to permit the mop to be readily moved under furniture.

It is an object of this invention to provide a handle that will break to permit a pivotal action and thus provide a more efficient mop.

A still further object of this invention is to provide a handle that may be locked as a single rigid handle or may be released to permit the breaking of the handle so that the two sections of the handle will lie on different axes.

Other objects of this invention may be apparent by reference to the accompanying detailed description and the drawings in which

Fig. 1 is an elevational view of the handle,

Fig. 2 is a partial view of the pivotal handle joint in an angle position,

Fig. 3 is an elevational view taken on line 3—3 of Fig. 2,

Fig. 4 is a view taken on line 4—4 of Fig. 2 and,

Fig. 5 illustrates an elevational view of a further embodiment of this invention.

Referring to the drawings and particularly Fig. 1 there is illustrated a handle 10 that may be used for a mop, brush or similar device in which the handle is provided with a thread 11 at one end thereof for attachment to the device in which it is to be used with. In this embodiment the handle 10 is provided in two sections 12 and 14. Referring to Fig. 2 the connecting joint is shown in an angle position in which the portion 14 is pivotally connected to the portion 12 by a pin 15. Referring to Fig. 3 it is apparent that portion 14 is provided with a projecting upper end 16 through which an aperture 17 is provided while the portion 12, Fig. 4, is provided with a slot 18 at one end thereof and a pair of apertures 19 and 20 positioned in alignment through the end of element 12. The apertures 19, 20 and 17 are shown in alignment and the pin 15 is mounted in a fixed relation in these apertures so that element 14 may be moved pivotally with respect to element 12. A sleeve or collar 21 is fitted about element 12 and elements 12 and 14 are provided with the same external diameter so that sleeve 21 will snugly fit both elements and can be slideably moved from the position illustrated in Fig. 1 to the position illustrated in Fig. 2 and back again as desired. The movement of sleeve 21 may be restricted that is, a pin 22 is provided in element 12 and a slot 23 is provided in sleeve 21 so that element 21 may be moved with relation to pin 22 downward until the end of the slot abuts with pin 22 as illustrated in Fig. 1.

2

Slot 23 is provided with a bayonet type of lock at its opposite end so that element 21 may be moved in an opposite direction as illustrated in Fig. 2 and rotated slightly to lock element 21 in the position as illustrated in Fig. 2. This is to retain element 21 out of the way when the handle is used in any of the angular positions, one element being at an angle to the other element.

It is apparent that in use handle 10 as shown in Fig. 1 may be affixed to a mop or brush or other such device by threadably securing the end 11 to the device or in the event a special connection is necessary end 11 may be threaded to an element (not shown) to make the necessary connection. In such use the device is similar to all present straight handles. However, in order that the handle may be used for mopping or scrubbing under furniture or appliances that are difficult to get under with a straight handle, the sleeve element 21 may be retracted to the position illustrated in Fig. 2 and by turning locked in this position, the handle 10 will then be pivotal in one plane to permit moving the lower portion of the handle 14 to any angular position down to a parallel relationship with the floor to thus permit easy access to the space under furniture or appliances.

A further embodiment of this invention is illustrated in Fig. 5 in which there are provided two portions of a handle 10A the upper portion 12A and the lower portion 14A. The lower portion of the handle 12A is provided with a threaded end 25 while the upper portion of the handle 14A is provided with a threaded end 26. The threaded portions 25 and 26 are mating threads and a sleeve 21A is provided to fit over the threaded portions 25 and 26. Sleeve 21A is provided with an internal thread 27 to mate with the threads 25 and 26. Element 21A should be constructed so that the threaded engagement is a fairly tight frictional fit or element 21A may be provided with plastic or rubber inserts 28 to insure a frictional gripping action between the sleeve 21A and the threaded ends 25 and 26. It is apparent that element 21A when turned in a clockwise direction will move downward and when turned in a counter-clockwise direction will move upward. Element 21A may be retracted until it abuts with either shoulder 29 of element 12A or 30 of element 14A. In this embodiment elements 12A and 14A must be pivotally connected in the same manner as elements 12 and 14 of Figs. 1, 2, 3 and 4.

Although handle 10 has been described in connection with a mop or brush or similar device it may be fitted to any floor bearing device such as a vacuum cleaner or polisher without departing from the spirit of this invention and although the handle 10 is shown with a sleeve 21 that is slideable from one position to another, the sleeve 21 may also be constructed as shown in the further embodiment with an internal thread while elements 12 and 14 are provided with a mating external thread thus permitting the setting of sleeve 21 to either side of the joint allowing movement thereof.

Various changes may be incorporated such as the shape of portion 12; it may be a straight handle or a specially designed handle without departing from the spirit of this invention and this invention shall be limited only by the appended claim.

What is claimed is:

A two piece handle in which the two pieces are joined by a pivot joint and in which the abutting ends of said pieces are provided with a similar thread and a sleeve threadably secured on said threaded ends, means to rotate said sleeve in either direction to a retracted position on one of said pieces to permit the pivot joint to break and means to rotate said sleeve in an opposite direction to move said sleeve back over said pivot joint

and retain said handle pieces in alignment with each other.
